ROTARY PRINTING PRESS WITH INTER-
CHANGEABLE PRINTING CYLINDER

George N. Auerbacher, South Orange, and Joseph R. Caulfield, West Norwood, N. J., assignors to Champlain Company, Inc., Bloomfield, N. J., a corporation of New York

Application February 24, 1949, Serial No. 78,044

22 Claims. (Cl. 101—181)

1

This invention relates to printing presses, and more particularly, though not necessarily, to a rubber plate printing press.

The primary object of the present invention is to generally improve printing presses. A more particular object is to provide a quick "throw-off" so arranged as to release the printing cylinder simultaneously from both the impression roll and the inking mechanism. Another object of the invention is to make it possible to change the diameter of the printing cylinder without necessitating a corresponding change in diameter for either the impression roll or the ink roll. In accordance with a feature and object of the present invention, the printing cylinder is mounted on normally fixed bearings, and the change in diameter of the printing cylinder is accommodated by a movement in approximately radial direction of both the impression roll and the inking mechanism. A further object of the invention is to so arrange the gearing for driving the impression roll and the ink roll as to accommodate the aforesaid movement of the rolls incident to a change in diameter of the printing cylinder.

Further objects are to facilitate rapid change of the printing cylinder; to make possible the use of any desired diameter of printing cylinder (within the minimum and maximum limits of the machine), independently of particular increments determined by gear teeth size or like factors; and to make it possible for the mechanism which moves the rolls for a change in printing cylinder size to be used also to adjust the printing pressure and the ink transfer pressure.

Further objects concern the application of the invention to multiple unit printing presses. One object is to make it possible to employ a single variable gear transmission or variable speed transmission to change the speed ratio between the rollers and the printing cylinder in all of the printing units. Another object is to provide quick release or throw-off simultaneously for all of the units. Still another object is to make it possible, by the inexpensive addition of one very small motor and overrunning clutch, to rotate the inking mechanisms of all of the units when the press is temporarily shut down.

To accomplish the foregoing objects, and other more specific objects which will hereinafter appear, our invention resides in the printing press elements and their relation one to another as are more particularly described in the following specification. The specification is accompanied by drawings in which:

2

Fig. 1 is a partially sectioned schematic elevation of a printing unit embodying features of our invention;

Fig. 2 is a similar view showing the rollers appropriately moved to accommodate a larger printing cylinder;

Fig. 3 is a schematic side elevation of a multiple unit printing press embodying features of the invention;

10 Fig. 4 is a plan view of the same;

Fig. 5 is a partially sectioned transverse elevation explanatory of the throw-off mechanism;

Figs. 6 and 7 are explanatory of the drive mechanism for the printing cylinder;

15 Fig. 8 schematically illustrates a multiple throw-off mechanism;

Fig. 9 is a side elevation schematically illustrating the addition of a drier, and variations in inking mechanism; and

20 Figs. 10 through 17 are schematic diagrams explanatory of the invention.

Referring to the drawing, and more particularly to Fig. 1, the printing unit there shown comprises a printing cylinder 12, an impression roll 14, and inking mechanism including an ink roll 16 which is normally in contact with the printing cylinder 12. The impression roll 14 is disposed below the printing cylinder 12 to receive a horizontal web 20 therebetween. The ink mechanism is sidewardly offset from the printing cylinder 12. The printing unit further comprises throw-off means to move the cylinder 12 a short distance in a diagonal direction, as indicated by the broken line position 12'. For this purpose the printing cylinder bearings 22 are carried in slides 24 which slope in the desired direction. The direction is such that the throw-off movement disengages the printing cylinder 12 simultaneously from the impression roll 14 and the ink roll 16.

40 The specific throw-off mechanism here shown comprises a shaft 26 extending across the press unit and carrying spaced eccentrics 28 which operate eccentric rods 30 connected to the bearings 22. Fig. 5 shows how spaced eccentrics 28 and connecting rods 30 are connected by shaft 26. The shaft 26 is operated by means of suitable handle 32. The handle may be provided with a reciprocable spring-pressed lock pin 34 co-operating with mating holes to lock the printing cylinder in either released or printing position.

Referring now to Figs. 1 and 2, the impression roll 14 and its bearings 36 are carried in vertical slides 38. The ends of the inking mechanism, 55 generally designated 40, are carried on spaced

horizontal slides 42 at the sides of the press. Appropriate adjusting means are provided for moving the impression roll and the inking mechanism along their respective slides, thereby accommodating a change in the size of the printing cylinder. This is illustrated by the change from the small diameter cylinder 12 shown in Fig. 1 to the large diameter cylinder 112 shown in Fig. 2. The printing cylinder bearings 22 retain their normally fixed center, and the change in diameter has been accommodated without changing the location of that center. The throw-off mechanism functions as before, and changes the location of the printing cylinder from the solid line position 112 to the dotted line position 112', thus releasing the printing cylinder simultaneously from both the impression roll 14 and the ink roll 16.

The mechanism for moving the impression roll bearings may be varied, but in the form here shown comprises a crank or hand wheel 44 turning a shaft 46 carrying spaced worms 48 meshing with worm gears 50 secured to the lower ends of screws 52 threadedly received by the bearings 36. It will be understood that the worm, worm gears and screws are disposed on opposite sides of the press to insure simultaneous and equal movement of both ends of the impression roll. If desired, some relative or independent adjustment may be provided in addition, to equalize the printing pressure when needed.

The mechanism for adjusting the inking mechanism may be of similar character, it comprising a hand wheel 54 turning a shaft 56 carrying a pair of spaced worms 58 meshing with worm gears 60 mounted on screws 62 threadedly received in spaced shoes at the sides of the inking mechanism.

The impression roll and the inking mechanism are preferably geared together, and are preferably driven by gearing so arranged as to accommodate the substantial movement already described. For this purpose the impression roll 14 is driven by a helical gear 64 of unusually great length, disposed with its axis in the direction of movement of the bearings 36. The helical gear 64 meshes with a helical gear 66 carried on the shaft 68 of the impression roll. It will be noted that in Fig. 1 the helical gear 66 is disposed near the upper end of the long helical gear 64, whereas in Fig. 2 it is disposed near the lower end. The long helical gear is restrained against axial movement, and remains in mesh with gear 66 during any change in position of the impression roll incident to a change in diameter of the printing cylinder. It will be understood that the long gear 64 need not be a helical gear as used in most modern sense, an obvious variant being a long worm at 64, meshing with a worm gear at 66, this being a special case of helical gearing. However, we believe the use of a multiple thread worm of large pitch, or, in other words, a helical gear in modern usage, to be preferable in order that the gearing be reversible, and also being there is no need for a marked reduction gear ratio such as would be produced by an ordinary single thread worm.

The drive for the inking mechanism is similar in that it employs a long gear 70 disposed in the direction of movement of the inking mechanism. This gear 70 meshes with a gear 72 on a shaft 74 carrying a roll 76 which forms a main part of the inking mechanism. As before explained, the gears 70 and 72 are preferably helical gears, although a worm and worm gear may also be em-

ployed. The long gear 70 is held against axial movement, and the driven gear 72 is disposed near the right end of the long gear 70 when the printing cylinder diameter is small, as is shown in Fig. 1, and is located near the left end of the long gear 70 when the printing cylinder diameter is large, as is shown in Fig. 2.

It has already been mentioned that the impression roll 14 and the inking mechanism 40 are preferably geared together, and in the present mechanism this is done in a very simple way by providing the helical gears 64 and 70 with meshed bevel gears 78 and 80, respectively. Power applied to either will drive both, and for reasons which will be clear later when describing a multiple unit press, the power is preferably applied to the horizontal gear 70 by means of a horizontal main drive shaft, broken sections of which are here indicated at 82. In simplest form the main shaft 82 may pass directly through the helical gear 70 and bevel gear 80. However, this is not at all essential, and if more convenient, the drive shaft may be disposed outside of or above the helical gears, and may be connected thereto by means of simple spur gearing, or chain and sprocket drives, or whatever may be considered most convenient in a particular press.

The printing cylinder itself is driven from the same ultimate source of power as the impression and ink rolls, but is preferably driven through an independent train of gearing. The gear ratio between the power source and either the printing cylinder or the rolls may be appropriately changed when the printing cylinder diameter is changed. In such case there is no need to change the diameter of the impression roll or ink roll, or to make any changes in the localized drive of the same.

Multiple printing units may be combined to form an "in-line" press, and such a press is schematically illustrated in Figs. 3 and 4 of the drawings. The particular press there shown provides a "straight-through" web lead, which is of advantage when printing on heavy material such as cardboard. The particular press shown in Figs. 3 and 4 comprises three printing units 84, 86 and 88, each of which may be like the unit already described in connection with Figs. 1 and 2 (although in Figs. 3 and 4 the web lead is shown from right to left, instead of from left to right, as shown in Figs. 1 and 2, which look from the geared side of the press).

The in-line press employs two main drive shafts, one being shown at 82, and the other at 90. In the present case the motor 92 is shown connected to main shaft 90, but it might equally well be connected to shaft 82. The form of drive from the motor is unimportant, and is here shown as a multiple V belt drive 94. Drive shaft 90 is connected to drive all of the printing cylinders in unison. However, for purposes of maintaining accurate registration of the multi-color printing operations the drive to the printing cylinders is preferably through appropriate compensating mechanisms, here illustrated as differential-gear compensating units 96. Such units are already known and require no detailed description, one form being described in U. S. patent to Grue 2,163,035, issued June 20, 1939. In principle such a unit comprises differential gearing, with power supplied to one sun gear, and taken out through the other sun gear, the planet gears being carried by means of a ring gear which may be turned very slowly in one direction or the other to feed in or take out a slight movement of the driven

sun gear relative to the power input. This slightly changes the position of the printing cylinder relative to that of the other printing cylinders. The corrective movement may be fed in by means of a small reversing motor under remote control, but for simplicity is here shown as utilizing the hand cranks indicated at 98.

Referring now to Fig. 6, it will be seen that the output of the compensating unit 96 is applied to a gear 108 meshing with an idler 102 and a driven gear 104 on one end of the printing cylinder shaft 106. This is carried in the bearings 22 for slight throw-off movement on the diagonal slides 24 previously referred to. It will be noted that the spur gears 102, 104 are preferably disposed with their centers at an angle corresponding generally to the angle of the slides 24. Moreover, the throw-off distance is preferably less than the length of the gear teeth, so that the gears will remain at least slightly in mesh even when the printing cylinder is released from the rolls. This is schematically shown in Fig. 7 in which the throw-off distance 108 is less than the length of the gear teeth 110. In this way synchronism and approximate registration of the multiple printing cylinders is retained after throw-off.

If desired, the printing cylinders may be released all at once. For this purpose the throw-off mechanisms may be operated hydraulically and connected to a common valve, or they may be operated by solenoids connected in a common electrical circuit. However, in Fig. 8 we show a simple mechanical interconnection in accordance with which the control handles 32 of the multiple printing units are all connected by links 114 so that movement of any one of the handles to throw-off position will move the others as well. It will be understood that handles 32 turn eccentrics 28 which move connecting rods 30 leading to the printing cylinder bearings 22 carried in diagonal slides 24. The impression rolls are schematically indicated at 14 and the ink rolls at 16. It will also be understood that a locking mechanism such as that shown at 34 in Fig. 5 could be omitted, or provided at only one point.

Reverting now to Figs. 3 and 4, the second main shaft 82 is connected to the helical gears 70 previously described and thus drives the impression and ink rolls. The connection between shafts 82 and 90 includes a variable speed drive 115, and in the present case this is shown as a so-called "P. I. V." (positive, infinite, variable) drive made by the Link Belt Company. The speed is gradually varied by a suitable control, here marked 117. An equivalent Reeves drive might also be employed. Indeed a simple "change-gear" connection might be used, but in such case the printing cylinder diameters employed would be limited by the available gear ratios. With the infinitely variable drive, the printing cylinder diameter may be made anything desired (within minimum and maximum limits) without reference to increments which might be necessitated by gear teeth size and consequent gear ratios. It may be observed that it might be prohibitive in cost to employ a "P. I. V." drive for each unit, but with the present arrangement using two main drive shafts, a single "P. I. V." drive is employed in common for all of the printing units.

Another advantage of the present arrangement is in simplifying the provision of means to continue rotation of the inking mechanism during "throw-off" or temporary shut down. This is desirable in order to prevent drying of the ink on the ink rolls. For this purpose a very small motor

116 is connected to the main shaft 82 through an overrunning clutch schematically shown at 118. The clutch is so faced that the motor 116 is normally idle and does not rotate. When the press is shut down, however, the motor 116 may be started, and in such case turns the shaft 82 and the inking mechanisms. The impression rolls are turned too, but this does no harm, for the web rests loosely and lightly on the slowly turning impression rolls, and is not driven thereby because the printing cylinders are in throw-off position. The connection between the "P. I. V." drive and the shaft 82 may include another overrunning clutch, indicated at 120, so that shaft 82 may be rotated by small motor 116 without having to drive the "P. I. V." drive, the shaft 90, the motor 92, and the printing cylinders.

The press of Figs. 3 and 4 is shown without driers. When dealing with a thin flexible web, 20 suitable driers may be interposed between the press units. However, when dealing with a coarse, stiff web it is better not to bend the same excessively, and a straight-through lead is preferable, as shown. Fortunately a stiff web is usually 25 an absorbent web, and it is possible to print in multiple colors without using driers between the press units. However, some drying may be desired at the end of the multiple printing operation, and such an arrangement is schematically 30 shown in Fig. 9, in which it will be seen that the three units 122, 124 and 126 are followed by a drier 128. The web lead is straight through except at the drier, where it is bent downward at 130 and then upward at 132.

35 Fig. 9 illustrates the fact that the particular inking mechanism employed may be varied, and for this purpose different inking mechanisms are shown in the units 122, 124 and 126, although it will be understood that in actual practice the 40 inking mechanisms in any one multiple press are ordinarily and preferably kept alike for the sake of uniformity. Referring to unit 122, the inking mechanism there shown is of a simple type comprising an intermediate ink roll 134 rotating with its lower portion immersed in an ink tank 136. Ink from roll 134 is transferred by means of a 45 transfer ink roll 138 to the printing cylinder 140.

More modern inking mechanisms of the so-called "Anilox" type may be employed. They 50 permit the use of more volatile inks and higher speed operation. They employ a doctor blade, which helps enclose the volatile ink against evaporation as well as splashing. A simple arrangement for this purpose is shown in unit 124, 55 in which an ink roll 142 runs in an ink tank 144. A doctor blade 146 bears against the roll 142. The roll 142 is a metal roll having an intagliated surface, and the doctor blade 146 is usually made of rubber.

60 The inking mechanism shown in unit 126 is another form of "Anilox" design. In this case an intagliated roll 148 runs in an ink tank 150 and is wiped by a doctor blade 152, much as previously described, but the ink is applied to the printing cylinder 154 through an intermediate transfer roll 156. The transfer roll 156 picks up the ink from the cells or pockets in the surface of the roll 148, and applies it to the surface of the printing cylinder 154.

70 With the conventional inking mechanism shown in unit 122, the amount of ink transfer is regulated by the pressure between rolls, partially between the first and second ink rolls 134 and 138, and partially between the ink roll 138 and the printing cylinder 140. In the present

apparatus the worm, worm gear and screw mechanism for changing the position of the inking mechanism for a change in cylinder diameter may be employed also to adjust the pressure between the ink roll and the printing cylinder. Similarly the worm, worm gear and screw mechanism for changing the position of the impression roll for a change in printing cylinder size, may be employed to regulate the printing pressure. In the "Anilox" type of inking mechanisms schematically shown in printing units 124 and 126, the amount of ink may be controlled by adjustment of the doctor blade pressure, and also by the pressure between the ink roll and the printing cylinder, the latter being adjustable by the worm, worm gear, and screw mechanism.

If a conventional inking mechanism is employed as schematically shown in unit 122, the press is reversible, that is, the web can be run through the press in either direction provided that the direction of rotation by the motor is appropriately changed. However, inking mechanism of the "Anilox" type should be run in only one direction because of the action of the doctor blade.

The particular inking mechanism shown in Figs. 1 and 2 is of the "Anilox" type, and corresponds nearly to that schematically shown in press unit 126 in Fig. 9. Referring to Figs. 1 and 2, the pressure of the intagliated roll 16 against the roll 16 is regulated by means of hand wheel 160, worms 162, worm gears 164, and screws 166. The position of the doctor blade 168 is regulated by means of hand wheel 170, worm 172, and worm gear 174. However, the inking mechanism is not a main feature of the present invention, other than that it should be adapted to and mounted for movement in the press, as already described.

The printing cylinder itself may be varied in type. That contemplated in the particular press here illustrated is a so-called "rubber plate" printing cylinder. This is a metal cylinder having a scored surface adapted to receive so-called "sticky back" rubber printing plates. However, the invention is not at all limited to the use of such a printing cylinder.

Some of the theory underlying the design of printing presses embodying the present invention may be described with reference to Fig. 10 of the drawing. In that figure the printing cylinder is shown at 176, the impression roll at 178, and the ink roll at 180. The roll 178 is disposed beneath cylinder 176 and is movable in a vertical direction over a large range, as is indicated by arrow 182. The ink roll 180 is displaced in horizontal relation to the cylinder 176 and is movable in horizontal direction over a large range, as is indicated by arrow 184. The throw-off movement of cylinder 176 is at an angle which preferably bisects the space between a radius running to roll 178 and another radius running to roll 180. In the present case the angle of direction line 186 is simply 45°, and the small throw-off movement is symbolized by the short distance between arrow heads at 186.

It is convenient to have the printing cylinder on top, where it is most readily changeable, and so that the printing on the web may be observed from above. However, it is not essential to locate the printing cylinder at the top, and Fig. 11 shows in similar symbolic form an arrangement in which the impression roll 188 is at the top, printing cylinder 190 is at the bottom, and ink roll 192 is horizontally displaced from the printing cylinder.

5 8
der. Here again, the throw-off movement indicated at 194 may be at an angle of 45°, thus releasing the cylinder equally from the rolls 188 and 192 but, of course, the movement of the printing cylinder is downward at 45° rather than upward at 45°.

10 Although convenient to deal with a horizontally moving web, that is not essential to the invention, and in Fig. 12 we show the invention applied to a vertical web 198. The printing cylinder is shown at 198, the impression roll at 200, and the ink roll at 202. The long range movement of the impression roll transversely of the web is symbolized by arrow 204, while the long range movement of the ink roll in the direction of the web is symbolized by arrow 206. The short throw-off movement of the printing cylinder is indicated at 208, and is in a direction bisecting the radii to the rolls, specifically at an angle of 45°.

25 Figs. 13 and 14 show how the web may be disposed at an angle, in this case at an angle 45°. In Fig. 13 the cylinder is shown at 210, the impression roll at 212, and the ink roll at 214. The long range movements of the rolls are indicated by arrows 216 and 218, respectively. The small throw-off movement of the cylinder is shown at 220, and it will be noted that in this case the throw-off movement is a vertical movement, yet 30 it satisfies the desideratum of bisecting the radii to the rolls in order that the printing cylinder be simultaneously released from both rolls.

35 In Fig. 14 the printing cylinder is shown at 222, the impression roll at 224, and the ink roll at 226. Their long range movements are indicated by the arrows 228 and 230. The short throw-off movement of the cylinder 222 is shown at 232. In this case the throw-off movement is a horizontal movement, but it satisfies the test 40 of dividing the angle between the radii extending to the rolls.

45 When dealing with a printing cylinder above a horizontal web, there may be difficulty in disposing the ink roll in truly horizontal relation to the printing cylinder. Reverting momentarily to Fig. 2 or to Fig. 9, it will be seen that the ink roll is often elevated somewhat, this resulting from the need to locate the entire inking mechanism above the web when dealing with even the smallest diameter printing cylinder. This 50 results in a modification of the preferred throw-off direction. Referring to Fig. 15, the impression roll 234 is disposed beneath the printing cylinder 236 as before, but the ink roll 238 is disposed on a radius 240 elevated from the horizontal. The long range movements are again indicated by the arrows 242 and 244. The desired short throw-off movement is indicated at 246. This is on a direction line bisecting the radii 248 and 240 leading to the rolls 234 and 238, respectively.

55 Referring now to Fig. 16, if the printing cylinder is changed to a new printing cylinder 250 double the previous diameter, the impression roll 234 is lowered, and the ink roll 238 is moved horizontally, as shown. The desired throw-off movement of the printing cylinder is indicated at 252, and is on a direction line which bisects the radii 254 and 256 leading to the rolls. The direction 60 of line 252 in Fig. 16 differs somewhat from the direction of line 246 in Fig. 15. In actual practice a throw-off direction is adopted which is preferably a compromise, as suggested by the dotted line 260. The line 260 is satisfactory for either 65 the smallest or the largest diameter printing cylinder.

inder, and its departure from theoretical direction may be quite small.

The arrangement of Figs. 15 and 16 assumes horizontal movement for the ink roll. This is convenient and desirable, but is not essential. Referring to Fig. 17, impression roll 262 is disposed beneath printing cylinder 264, as before, and ink roll 266 is disposed on a radius elevated somewhat from horizontal, as before. The long range movement of roll 262 is vertical, as indicated by arrow 268. The long range movement of roll 266, instead of being horizontal, is shown to be radial, as indicated by arrow 270. The short throw-off movement of the cylinder is indicated at 272. This may be in a direction bisecting the radii to the rolls. No compromise is needed because there is no change of direction when changing the size of the printing cylinder. However, in this arrangement the long helical gear for driving the inking mechanism is disposed at the angle 270, and the connection to the main drive shaft is appropriately modified.

Note that these matters need not arise when using the other arrangements shown in Figs. 11 through 14 of the drawing. For example, in Fig. 11 the ink roll may be disposed in truly horizontal relation to the printing cylinder, for the web is above the ink roll, and there is unlimited room beneath the ink roll for the ink tank and other inking mechanism. Similar remark would apply to Figs. 12, 13 and 14, if the ink tank, etc. is shaped to clear the web.

It is believed that the construction and operation of our improved printing press, as well as the advantages thereof, will be apparent from the foregoing detailed description. The particular arrangement shown places the printing on top of the web where it is visible to the operator, and this is convenient not only for adjusting the registration of multiple printing units, but even with a single unit, when the press is combined with subsequent fabricating operations, such as perforating, punching, and so on. The location of the printing cylinder facilitates rapid change, for it is located on top in the most convenient place and is readily removed without difficulty. The printing cylinder diameter may be changed without changing the diameter of the impression roll or the inking rolls. The change of printing cylinder diameter may be made without necessitating a laborious or inconvenient change in gear ratio. There is no need to make special gears, or to keep a large stock of change-gears on hand to effect proper linear speed. Instead the printing cylinder size may be changed in any desired increments, without limitation caused by gear tooth size. The change in cylinder size may be effected rapidly by simply backing away the impression and ink rolls, and changing the speed at the "P. I. V." drive. No change in gearing need be made when backing away the impression and ink rolls.

The web may be released by a rapid and convenient throw-off, and a single throw-off movement serves to separate the printing cylinder from both the impression roll and the inking roll. The throw-off operation may be ganged for simultaneous control of all units. The gear relation between the impression roll and the ink roll is such that it is only necessary to synchronize one or the other with the printing cylinder. Because this adjustment is made between the two main drive shafts, a single adjustment serves for all of the printing units. The inking mechanism may be of the aniline type

using smooth rolls, or of the "Anilox" type using an intagliated roll and doctor blade, and in either case a greater or lesser number of ink rolls may be employed as desired. The drive of both the

5 impression and ink rolls is from a common main shaft, and is divorced from the drive of the cylinders, which is from another common main shaft. Such an arrangement is convenient not only in requiring but one "P. I. V." drive for all 10 units, but also in making it conveniently possible to employ individual independent register control or compensating units for the different printing cylinders. The inking mechanisms may be kept rotating when the press is temporarily shut 15 down, in order to prevent drying of the ink on the rolls. A single small motor takes care of this for all of the printing units.

Many of the features are of value independently 20 of the others. For example, the quick throw-off for moving the printing cylinder at an angle having components for simultaneous separation from both the impression roll and the inking roll would be of value in a press having a fixed cylinder size. Conversely, the long helical gear 25 arrangement affording movement of the rolls to accommodate a change in printing cylinder size would be of value even without diagonal throw-off of the printing cylinder. Inking mechanisms of varied type may be employed. 30 Other forms of speed adjustment than the "P. I. V." drive may be used. Long worms may be used in lieu of long helical gears, or short gears splined for axial movement along splined shafts, and indeed flexible shafts, or shafts with 35 universal joints, might be employed to accommodate the lateral movement of the rolls. Other forms of compensating mechanism for registration may be used in lieu of the differential gears mentioned.

40 These and numerous other changes may be made without departing from the spirit of the invention as sought to be defined in the following claims. In some claims the printing cylinder is said to have a "normally fixed center." This has reference to the change of diameter, and does not exclude the temporary displacement for throw-off. In some claims the ink roll is said to be sidewardly offset from the printing cylinder, which is intended to include the somewhat elevated position of Figs. 1, 2, 15, 16, and 17, as well as the truly horizontal offset shown in Figs. 10 and 11.

45 The reference to the impression roll being below the printing cylinder, and the ink roll being sidewardly offset, while the throw-off movement is in a diagonal direction, is to be constructed in a relative sense rather than an absolute sense, for the entire group of rolls may be bodily re-oriented, as was explained in connection with Figs. 10 through 17, without changing the significant inter-relation between the cylinder and rolls as contemplated and taught by the present disclosure. For convenience and clarity in definition and simple terms "vertical," "horizontal," and "diagonal" are employed in the 50 claims, but are meant in a relative sense. Thus the movement of the impression roll, while usually vertical, would not be vertical in Figs. 12, 13 and 14, and the movement of the inking mechanism, while usually horizontal, would not be horizontal in Figs. 12, 13, 14 and 17. Similarly, the throw-off movement of the printing cylinder, although 55 usually diagonal, would not be diagonal in Fig. 13

We claim:

1. A printing unit comprising normally fixed center bearings and a printing cylinder carried thereby, impression roll bearings and an impression roll carried thereby beneath said printing cylinder to receive a horizontal web therebetween, vertical slides for said impression roll bearings, adjusting means for moving said impression roll bearings for a substantial distance along said slides to accommodate a substantial change in the size of the printing cylinder, inking mechanism including an ink roll sidewardly offset from said printing cylinder, horizontal slides for said inking mechanism, adjustment means for moving said inking mechanism for a substantial distance along said slides to accommodate a change in the size of the printing cylinder, a power source for driving the printing cylinder and for driving the impression roll, and variable speed gearing of the positive infinitely variable type between said printing cylinder and the impression roll, said variable speed gearing providing a large overall range of speed ratio in minute graduations, in order to maintain proper relative speed upon change in the size of the printing cylinder, whereby it is unnecessary to change the size of the roll.

2. A printing unit comprising normally fixed center bearings and a printing cylinder carried thereby, impression roll bearings and an impression roll carried thereby beneath said printing cylinder to receive a horizontal web therebetween, vertical slides for said impression roll bearings, worm, worm gear and screw adjusting means for moving said impression roll bearings for a substantial distance along said slides to accommodate a change in the size of the printing cylinder, inking mechanism including an ink roll sidewardly offset from said printing cylinder, horizontal slides for said inking mechanism, worm, worm gear and screw adjustment means for moving said inking mechanism for a substantial distance along said slides to accommodate a change in the size of the printing cylinder, means gearing said ink roll and said impression roll to one another for rotation in fixed ratio, a power source for driving the printing cylinder and for driving the impression roll and ink roll, and variable speed gearing of the positive infinitely variable type between said printing cylinder and the rolls, said variable speed gearing providing a large overall range of speed ratio in minute graduations, in order to maintain proper relative speed upon change in the size of the printing cylinder, whereby it is unnecessary to change the size of the rolls.

3. A printing unit comprising normally fixed center bearings and a printing cylinder carried thereby, impression roll bearings and an impression roll carried thereby beneath said cylinder, vertical slides and associated mechanism for raising or lowering the impression roll, inking mechanism disposed at one side of the printing cylinder, horizontal slides and associated mechanism for moving the inking mechanism toward or away from the printing cylinder, a gear of great axial length meshing with a gear on the inking mechanism for driving the inking mechanism, the axis of said gear being parallel to the horizontal slides, a gear of great axial length meshing with a gear on the impression roll for driving the impression roll, the axis of said gear being parallel to the vertical slides, gears connecting said long gears, said long gears having a length corresponding to the desired range of ad-

justment and accommodating adjustment of the impression roll and inking mechanism in order to accommodate a change in size of printing cylinder.

4. A printing unit comprising normally fixed center bearings and a printing cylinder carried thereby, impression roll bearings and an impression roll carried thereby beneath said cylinder, vertical slides and associated mechanism for raising or lowering the impression roll, inking mechanism disposed at one side of the printing cylinder, horizontal slides and associated mechanism for moving the inking mechanism along the slides, a helical gear of great axial length meshing with a helical gear on the inking mechanism for driving the inking mechanism, the axis of said gear being parallel to the horizontal slides, a helical gear of great axial length meshing with a helical gear on the impression roll for driving the impression roll, the axis of said gear being parallel to the vertical slides, and gears connecting said helical gears, said long helical gears having a length corresponding to the desired range of adjustment and accommodating adjustment of the impression roll and inking mechanism in order to accommodate a change in size of printing cylinder.

5. A printing unit comprising normally fixed center bearings and a printing cylinder carried thereby, impression roll bearings and an impression roll carried thereby beneath said cylinder, vertical slides and associated mechanism for raising or lowering the impression roll, inking mechanism disposed at one side of the printing cylinder, horizontal slides and associated mechanism for moving the inking mechanism along the slides, a gear of great axial length meshing with a gear on the inking mechanism for driving the inking mechanism, the axis of said gear being parallel to the horizontal slides, a gear of great axial length meshing with a gear on the impression roll for driving the impression roll, the axis of said gear being parallel to the vertical slides, gears connecting said long gears, said long gears having a length corresponding to the desired range of adjustment and accommodating adjustment of the impression roll and inking mechanism in order to accommodate a change in size of printing cylinder, a power source to drive the printing cylinder and also to drive one of the long gears, and variable speed gearing between said power source and either the printing cylinder or the long gears to maintain desired speed ratio when the size of the printing cylinder is changed.

6. A printing unit comprising normally fixed center bearings and a printing cylinder carried thereby, impression roll bearings and an impression roll carried thereby beneath said cylinder, vertical slides and associated mechanism for raising or lowering the impression roll over a substantial distance, inking mechanism disposed at one side of the printing cylinder, horizontal slides and associated mechanism for moving the inking mechanism along the slides for a substantial distance, a helical gear of great axial length meshing with a helical gear on the inking mechanism for driving the inking mechanism, the axis of said gear being parallel to the horizontal slides, a helical gear of great axial length meshing with a helical gear on the impression roll for driving the impression roll, the axis of said gear being parallel to the vertical slides, bevel gears connecting said helical gears, said long helical gears having a length corresponding to the desired range of adjustment and accommodating adjustment of the impression roll and inking

mechanism in order to accommodate a change in size of printing cylinder, a power source to drive the printing cylinder and also to drive the long horizontal helical gear, and variable speed gearing between said power source and said helical gear to maintain the desired linear speed when the size of the printing cylinder is changed.

7. An in-line press comprising a plurality of printing units, each of said units comprising normally fixed center bearings and a printing cylinder carried thereby, impression roll bearings and an impression roll carried thereby beneath said cylinder, inking mechanism disposed at one side of the printing cylinder, gearing connecting said roll and said inking mechanism, a first main shaft extending longitudinally of the in-line press for driving all of the printing cylinders, compensating means between said main shaft and each of said printing cylinders for registration, said compensating means affording adjustment of the cylinders relative to the main shaft and relative to one another, a second main shaft extending longitudinally of said in-line press and connected to the aforesaid rolls and inking mechanism, and a power source to drive both main line shafts.

8. An in-line press comprising a plurality of printing units, each of said units comprising normally fixed center bearings and a printing cylinder carried thereby, impression roll bearings and an impression roll carried thereby beneath said cylinder, vertical slides and associated mechanism for raising or lowering the impression roll over a substantial distance, inking mechanism disposed at one side of the printing cylinder, horizontal slides and adjustment mechanism for moving the inking mechanism along the slides for a substantial distance, gearing connecting said roll and said inking mechanism, said gearing accommodating adjustment of the impression roll and inking mechanism over a substantial distance to accommodate a change in size of printing cylinder, a first main shaft extending longitudinally of the in-line press for driving all of the printing cylinders, compensating means between said main shaft and each of said printing cylinders for registration, said compensating means affording adjustment of the cylinder relative to the main shaft and relative to one another, a second main shaft extending longitudinally of said in-line press and connected to the aforesaid rolls, a power source to drive both main shafts, and variable speed gearing between said power source and one of said main shafts to maintain the desired linear speed when the size of the printing cylinders is changed.

9. An in-line press having a straight-through web lead, said press comprising a plurality of printing units, each of said units comprising normally fixed center bearings and a printing cylinder carried thereby, impression roll bearings and an impression roll carried thereby beneath said cylinder, vertical slides and associated mechanism for raising or lowering the impression roll over a substantial distance, inking mechanism disposed at one side of the printing cylinder, horizontal slides and adjustment mechanism for moving the inking mechanism along the slides for a substantial distance, a helical gear of great axial length meshing with a helical gear on the inking mechanism for driving the inking mechanism, the axis of said gear being parallel to the horizontal slides, a helical gear of great axial length meshing with a helical gear on the impression roll for driving the impression roll, the

axis of said gear being parallel to the vertical slides, gears connecting said long helical gears, said long helical gears having a length corresponding to the desired range of adjustment and accommodating adjustment of the impression roll and inking mechanism in order to accommodate a change in size of printing cylinder, a first main shaft extending longitudinally of the in-line press for driving all of the printing cylinders, a second main shaft extending longitudinally of said in-line press and connected to the aforesaid long helical gears, a power source to drive both main shafts, and variable speed gearing between said power source and one of said main shafts to maintain the desired linear speed when the size of the printing cylinders is changed.

10. A printing unit comprising a printing cylinder, an impression roll, inking mechanism including an ink roll, means gearing said rolls together independently of the printing cylinder, a power source to drive the printing cylinder and the rolls, and variable speed gearing of the positive infinitely variable type between said printing cylinder and the rolls, said variable speed gearing providing a large overall range of speed ratio in minute graduations, in order to provide a desired speed ratio for any desired cylinder diameter.

11. A printing unit comprising a printing cylinder, an ink roll, an impression roll, means for moving the ink roll toward or away from the printing cylinder to accommodate a change in size of printing cylinder, means for moving the impression roll toward or away from the printing cylinder to accommodate a change in size of printing cylinder, means connecting said rolls together for simultaneous rotation, a power source, means connecting said power source to said rolls, the connections being such as to accommodate the movement of the rolls relative to the printing cylinder, means connecting said power source to the printing cylinder, and variable speed gearing of the positive infinitely variable type between said printing cylinder and the rolls, said variable speed gearing providing a large overall range of speed ratio in minute graduations, in order to maintain desired speed ratio when the size of the printing cylinder is changed.

12. A printing unit comprising normally fixed center bearings and a printing cylinder carried thereby, impression roll bearings and an impression roll carried thereby, slides and associated mechanism for moving the impression roll over a substantial distance, a helical gear of great axial length meshing with a helical gear on the impression roll for driving the impression roll, the axis of said gear being parallel to the slides, said long helical gear having a length corresponding to the desired range of adjustment and accommodating adjustment of the impression roll in order to accommodate a change in size of printing cylinder.

13. A printing unit comprising normally fixed center bearings and a printing cylinder carried thereby, inking mechanism disposed at the printing cylinder, slides and associated mechanism for moving the inking mechanism along the slides for a substantial distance, a helical gear of great axial length meshing with a helical gear on the inking mechanism for driving the inking mechanism, the axis of said gear being parallel to the slides, said long helical gear having a length corresponding to the desired range of adjustment

15

and accommodating adjustment of the inking mechanism in order to accommodate a change in size of printing cylinder.

14. A printing unit comprising normally fixed center bearings and a printing cylinder carried thereby, impression roll bearings and an impression roll carried thereby, slides and associated mechanism for moving the impression roll over a substantial distance, a helical gear of great axial length meshing with a helical gear on the impression roll for driving the impression roll, the axis of said gear being parallel to the slides, said long helical gear having a length corresponding to the desired range of adjustment and accommodating adjustment of the impression roll in order to accommodate a change in size of printing cylinder, a power source to drive the printing cylinder and also to drive the long helical gear, and variable speed gearing of the positive infinitely variable type between said power source and said helical gear to maintain the desired linear speed when the size of the printing cylinder is changed.

15. A printing unit comprising normally fixed center bearings and a printing cylinder carried thereby, inking mechanism disposed at the printing cylinder, slides and associated mechanism for moving the inking mechanism along the slides for a substantial distance, a helical gear of great axial length meshing with a helical gear on the inking mechanism for driving the inking mechanism, the axis of said gear being parallel to the slides, said long helical gear having a length corresponding to the desired range of adjustment and accommodating adjustment of the inking mechanism in order to accommodate a change in size of printing cylinder, a power source to drive the printing cylinder and also to drive the long helical gear, and variable speed gearing of the positive infinitely variable type between said power source and said helical gear to maintain the desired linear speed when the size of the printing cylinder is changed.

16. An in-line press comprising a plurality of printing units, each of said units comprising normally fixed center bearings and a printing cylinder carried thereby, impression roll bearings and an impression roll carried thereby, a first main shaft extending longitudinally of the in-line press for driving all of the printing cylinders, compensating means between said main shaft and each of said printing cylinders for registration, said compensating means affording adjustment of the cylinders relative to the main shaft and relative to one another, a second main shaft extending longitudinally of said in-line press and connected to the aforesaid impression rolls, and a power source to drive both main line shafts.

17. An in-line press comprising a plurality of printing units, each of said units comprising normally fixed center bearings and a printing cylinder carried thereby, inking mechanism disposed at the printing cylinder, a first main shaft extending longitudinally of the in-line press for driving all of the printing cylinders, compensating means between said main shaft and each of said printing cylinders for registration, said compensating means affording adjustment of the cylinders relative to the main shaft and relative to one another, a second main shaft extending longitudinally of said in-line press and connected to the aforesaid inking mechanisms, and a power source to drive both main line shafts.

18. An in-line press comprising a plurality of

16

printing units, each of said units comprising normally fixed center bearings and a printing cylinder carried thereby, impression roll bearings and an impression roll carried thereby, slides and associated mechanism for moving the impression roll over a substantial distance, a first main shaft extending longitudinally of the in-line press for driving all of the printing cylinders, compensating means between said main shaft and each of said printing cylinders for registration, said compensating means affording adjustment of the cylinders relative to the main shaft and relative to one another, a second main shaft extending longitudinally of said in-line press and connected to the aforesaid impression rolls, a power source to drive both main shafts, and variable speed gearing between said power source and one of said main shafts to maintain the desired linear speed when the size of the printing cylinders is changed.

19. An in-line press comprising a plurality of printing units, each of said units comprising normally fixed center bearings and a printing cylinder carried thereby, inking mechanism disposed at the printing cylinder, slides and adjustment mechanism for moving the inking mechanism along the slides of a substantial distance, a first main shaft extending longitudinally of the in-line press for driving all of the printing cylinders, compensating means between said main shaft and each of said printing cylinders for registration, said compensating means affording adjustment of the cylinders relative to the main shaft and relative to one another, a second main shaft extending longitudinally of said in-line press and connected to the aforesaid inking mechanisms, a power source to drive both main shafts, and variable speed gearing between said power source and one of said main shafts to maintain the desired linear speed when the size of the printing cylinders is changed.

20. An in-line press having a straight-through web lead, said press comprising a plurality of printing units, each of said units comprising normally fixed center bearings and a printing cylinder carried thereby, impression roll bearings and an impression roll carried thereby, slides and associated mechanism for moving the impression roll over a substantial distance, a helical gear of great axial length meshing with a helical gear on the impression roll for driving the impression roll, the axis of said gear being parallel to the slides, said long helical gear having a length corresponding to the desired range of adjustment and accommodating adjustment of the impression roll in order to accommodate a change in size of printing cylinder, a first main shaft extending longitudinally of the in-line press for driving all of the printing cylinders, a second main shaft extending longitudinally of said in-line press and connected to the aforesaid long helical gears, a power source to drive both main shafts, and variable speed gearing between said power source and one of said main shafts to maintain the desired linear speed when the size of the printing cylinders is changed.

21. An in-line press having a straight-through web lead, said press comprising a plurality of printing units, each of said units comprising normally fixed center bearings and a printing cylinder carried thereby, inking mechanism disposed at the printing cylinder, slides and adjustment mechanism for moving the inking mechanism along the slides for a substantial distance, a heli-

cal gear of great axial length meshing with a helical gear on the inking mechanism for driving the inking mechanism, the axis of said gear being parallel to the slides, said long helical gears having a length corresponding to the desired range of adjustment and accommodating adjustment of the inking mechanism in order to accommodate a change in size of printing cylinder, a first main shaft extending longitudinally of the in-line press for driving all of the printing cylinders, a second main shaft extending longitudinally of said in-line press and connected to the aforesaid long helical gears, a power source to drive both main shafts, and variable speed gearing between said power source and one of said main shafts to maintain the desired linear speed when the size of the printing cylinders is changed.

22. In a printing unit, bearings for a shaft, slides and associated mechanism for moving the bearings along said slides over a substantial distance for a desired range of adjustment, a helical gear of great axial length disposed outside one of said bearings with its axis in the direction of movement of the bearings, said gear being fixed against axial movement, a helical gear on said shaft meshing with said long helical gear, said

5

long helical gear having a length corresponding to the desired range of adjustment and thereby accommodating the movement of the shaft and bearings along the slides.
